UNITED STATES PATENT OFFICE.

LEOPOLD STICKLEY, OF FAYETTEVILLE, NEW YORK.

DESIGN FOR A BOTTOM FOR CHAIRS OR SIMILAR ARTICLES.

44,776.

Specification for Design.

Patented Oct. 21, 1913.

Application filed July 27, 1911. Serial No. 640,944. Term of patent 14 years.

To all whom it may concern:

Be it known that I, LEOPOLD STICKLEY, a citizen of the United States, residing at the village of Fayetteville, in the county of Onondaga, State of New York, have invented a new, original, and ornamental Design for Bottoms for Chairs or Similar Articles, of which the following is a specification, reference being had to the accompanying drawing, forming a part thereof, in which is shown a perspective view of my design.

The design comprises a rectangular chair bottom having the raised rear portion *a*, the

concaved portion *b*, adjacent thereto gradually increasing thickness as to approach the front edges of the bottom and terminating in a rounded portion.

What I claim is:

The ornamental design for a bottom for chairs or similar articles as shown and described.

LEOPOLD STICKLEY.
